C. L. SCHWARTZ

IRONER

Filed March 16, 1922

Inventor
Chester L. Schwartz.

By Ralph J. Burton.

Attorney

UNITED STATES PATENT OFFICE.

CHESTER L. SCHWARTZ, OF DETROIT, MICHIGAN.

IRONER.

Application filed March 16, 1922. Serial No. 544,178.

To all whom it may concern:

Be it known that I, CHESTER L. SCHWARTZ, a citizen of the United States, residing at Detroit, in the county of Wayne and State 5 of Michigan, have invented certain new and useful Improvements in Ironers, of which the following is a specification.

My invention relates to improvements in ironers, particularly to improvements in 10 power driven ironers adapted for foot operation.

The object is to provide a power driven ironer comprising a rotatable roll and a 15 movable shoe, a support for one end of the roll so arranged that garments of greater width than the length of the roll may be easily ironed in that clearance from one end is provided underneath such end of the roll; and also to provide a shoe so mounted as to 20 be automatically capable of accommodating itself to varying thicknesses of garments between the shoe and roll; and, further, in connection with a foot operated shoe, adjustable yielding connections adapted to 25 press the shoe toward the roll.

The above and other objects together with details of construction will more fully appear from the following description, appended claim and accompanying drawings, 30 in which:

Fig. 1 is an end elevation partly broken away.

Fig. 2 is a sectional view taken on line 35 2-2 of Fig. 1.

Fig. 3 is a front elevation of my ironer partly broken away.

Fig. 4 is a view taken on line 4-4 of 40 Fig. 3.

And Fig. 5 is a view looking in the direction of the arrows 5-5, in Fig. 1.

In the drawings let 10 indicate the ironer frame, 11 the rotatable roll, 12 the movable shoe pivoted at 13 to a support 14, one of 45 which is provided for each end of the shoe. My shoe is adapted for foot actuation.

I provide a foot pedal 15, held yieldingly upward with the shoe in the retracted position, by means of a spring 16. The foot 50 pedal board extends lengthwise the frame to permit easy operating. Extending under-

neath the bed of the machine is a shaft 17 to which the foot pedal is connected by means of a long link 18, and a short arm 19 mounted on the shaft, so that depression of 55 the foot pedal will rotate the shaft.

Pivots mounted at each end of the machine is a bell crank arm 20, one end of which extends under the bed of the ironer and is connected with the shaft 17 by means of pivoted links 21, so that when the shaft is rotated by the foot pedal the end of the arms engaged by the links are depressed. The upper ends of the arms 20 are perforated and extending through such perforations are rods 22. These rods are connected at one end to the shoe, and they are adapted to hold said shoe yieldingly toward the roll by means of spiral springs 23, which encircle the rods and bear at one end against the arms 20 and at the other against a stop 24. The tension of this spring is regulated by means of a pin 25, which is received in perforations 26 through the end of the rod 22 that extends beyond the arm 20. 75

What I claim is:

In an ironer, a frame provided with a pair of angular supporting arms, a roll supported between said arms to provide free clearance underneath the roll from the arms, a pair of standards carried by the frame positioned on the opposite side of the roll, an arcuate shoe pivotally mounted between said standards to be swung toward and away from said roll, 80 pedal operated mechanism, a pair of bell crank levers connected with said pedal operated mechanism to be actuated thereby, a pair of connecting links secured to said shoe, one extending slidably through each of said bell crank levers, each connecting link being provided with spaced apart stops one on each side of the bell crank lever, a coil spring encircling the connecting link between the bell crank lever and the stop nearest the 85 shoe, to hold the shoe toward the roll and adapted to hold the bell crank lever against the stop farthest from the shoe, and a spring engaging said pedal operated mechanism and exerting pressure thereon to normally hold the shoe away from the roll. 100

CHESTER L. SCHWARTZ.
